United States Patent Office

Des. 203,710
Patented Feb. 8, 1966

203,710

DISPENSER CAP OR SIMILAR ARTICLE

Gordon K. Woodard, 14155 Magnolia Blvd., Apt. 354,
Van Nuys, Calif.

Filed June 1, 1964, Ser. No. 80,214

Term of patent 14 years

(Cl. D58—26)

FIGURE 1 is a perspective view of a dispenser cap or similar article showing my new design;

FIGURE 2 is a side elevational view;

FIGURE 3 is an elevational view taken from the right of FIGURE 2;

FIGURE 4 is a plan view taken from the top of FIGURE 2;

FIGURE 5 is a side elevational view similar to FIGURE 2 in open position; and

FIG. 6 is an elevational view on a reduced scale looking from the left of FIG. 5.

I claim:

The ornamental design for a dispenser cap or similar article, substantially as shown.
